UNITED STATES PATENT OFFICE.

HENRY E. BURKET, OF CHICAGO, ILLINOIS.

RADIO RECEIVING SYSTEM AND UNIT.

Application filed July 10, 1925. Serial No. 42,651.

This invention has to do with certain improvements in radio receiving systems. The invention has reference particularly to improvements in systems for receiving speech and similar signals by the use of carrier waves.

One object of the invention is to provide means for amplifying the received signals without the need of using plural coil transformers between the stages or between detector or amplifier tubes. That is to say, it is an object of the invention to avoid the need of using transformers having more than one coil, the arrangement being such that the desired translation of energy may be performed by the use of a reactance coil together with suitable co-operating instrumentalities such as grid leaks, condensers, etc.

Another feature of the invention relates to the provision of a self-contained translation and amplifying unit including the necessary elements. In this connection, it is an object to bring the necessary parts of this unit into proper relation and co-operation within a self-contained unit having certain terminal binding posts or connections for attachment directly to the proper portions of the system such as the grid, the plate, the positive side of the battery, the negative filament, etc.

A further object in connection with the construction of the unit is to bring all of the necessary parts thereof into a very compact and closely co-ordinated structure of small size and so arranged that self-interference as well as cross interference with other portions of the circuit will be eliminated.

Other objects and uses of the invention will appear from a detailed description of the same, which consists in the features of construction and combinations of parts herein-after described and claimed.

In the drawings:

Figure 1 shows diagrammatically a series of connections for a receiving circuit establishing a single stage of audio frequency amplification by means of a unit and connections embodying the features of the present invention;

Fig. 2 shows diagrammatically the connections of the unit itself which is inserted into and constitutes a portion of the complete circuit illustrated in Fig. 1;

Fig. 3 shows diagrammatically another circuit or series of connections embodying the features of the present invention, but in which circuit the arrangement of the unit

connections is reversed as compared to Fig. 1;

Fig. 4 shows diagrammatically the connections of the unit of the circuit illustrated in Fig. 3;

Fig. 5 shows a plan view of the assembled unit itself, having the top plate thereof marked to correspond to the terminal connections of the circuit illustrated in Figs. 1 and 2;

Fig. 6 shows a side view corresponding to Fig. 5 with one of the side plates removed;

Fig. 7 shows a view at right angles to that of Fig. 6, one of the side plates being cut away so as to illustrate the interior construction;

Fig. 8 shows diagrammatically a circuit similar to that of Fig. 1, but modified by the substitution of a tapped inductance instead of the plain inductance in the unit of Fig. 1;

Fig. 9 shows diagrammatically the connections of the modified unit which is incorporated in the arrangement of Fig. 8;

Fig. 10, shows diagrammatically another circuit corresponding to that of Fig. 3, but with a tapped inductance instead of the plain inductance of the unit of Fig. 3; and

Fig. 11, shows diagrammatically the connections of the modified unit which is incorporated in the arrangement of Fig. 10.

Referring first to Figs. 1 and 2, the circuit illustrated in Fig. 1 includes the detector tube 8 and the amplifier tube 9 for the first stage of audio frequency amplification. The tube 8 is provided with the filament 10, grid 11, and plate 12, and the tube 9 is provided with the filament 13, grid 14 and plate 15, all in accordance with standard practice. The A battery 16 is provided for illuminating the filaments 10 and 13, having its positive side connected to the bus-bar 17 and its negative side connected to the bus-bar 18. The rheostat 19 for the detector tube filament is placed preferably in the negative lead and the rheostat 20 for the amplifier tube filament is preferably placed in the positive lead as illustrated. This arrangement will facilitate the tuning and adjustment of the circuit, since the adjustment of the filaments will in this case not interfere with the circuit adjustment.

The incoming signals may be delivered to the detector tube in any convenient manner and under any desired system of tubing. The arrangement illustrated is a convenient one, including a tuner 21 having the primary and secondary coils 22 and 23 respectively. The primary coil 22 is connected between the aerial 24 and the ground 25. A variable con-

denser 26 is connected across the secondary coil 23 so as to tune the same to incoming signals. One side of the coil 23 and condenser 26 is connected to the grid 11 by a lead 27, and the other side is connected to a reactance coil 28 preferably comprising a single coil having a core 29. The other side of this coil is connected by a lead 30 with the positive side of the A battery. This coil 28 or 28^a may be used in place of the usual form of grid leak, either with or without the other features of invention herein disclosed; and when said coil 28 is used in place of a grid leak it should have a reactance of approximately 200 henries and a resistance of 1,000 to 4,000 ohms. The plate 12 of the detector tube 8 is connected by a lead 31 with the resistance 32. The other side of this resistance is connected by a lead 33 with the positive side of the battery 34 (preferably a 22½ volt battery) and the negative side of said battery is connected by a lead 35 with the positive bus-bar 18 of the A battery. The resistance 32 is, therefore, in effect connected across the plate and filament of the detector tube.

The plate end of the resistance 32 is also connected to one side of a small fixed condenser 36 the other side of which connects by a lead 37 with the grid 14 of the amplifier tube 9.

The reactance coil 38 preferably including a core 39 is connected across the grid 14 and the filament 13 of the amplifier tube 9, and, therefore, also in parallel with the resistance 32 (including the battery 34).

The output (illustrated as a headphone 40) is connected across the plate 15 and the positive side of the circuit by the leads 41 and 42. Preferably also a booster battery (for example, a 90 volt battery) 43 is included in the lead 42 so as to give more power in the headphone.

The resistance 32 preferably has a value of approximately one-half meg-ohm or less, the fixed condenser 36 is preferably of approximately .06 mf. capacity, and the choke coil or reactance coil 38 is preferably of approximately 4444 turns or 100 to 200 henries. However, it will be understood that the resistance, capacity, and number of turns above specified will depend entirely upon the conditions and other elements of the circuit under consideration, and therefore, by mentioning the above amounts, I do not intend to limit myself thereto except as I may do so in the claims.

It will be noted that the small fixed condenser, resistance, and reactance, are all brought together at more or less of a common point in the circuit and intermediate between the tubes. It is, therefore, possible to assemble all of these parts conveniently as a single unit having the necessary terminal connections, so that it may be easily set into or removed from the circuit as a whole. I have,

therefore, illustrated these parts diagrammatically in Fig. 2 as assembled upon a common plate 44, having the terminal or binding posts 45, 46, 47 and 48. The post 45 is intended to connect with the plate 12 and is, therefore, marked P, the post 46 is intended to be connected to the grid 14 and is, therefore, marked G, the post 47 is intended to be connected to the positive side of the battery 43 and is, therefore, marked Plus, and the post 48 is intended to be connected to the negative side of the filament 43, and is, therefore, marked N. F.

In Figs. 5, 6 and 7 I have illustrated a typical construction of unit corresponding to the diagram layout of Fig. 2. It includes the coil 49 built onto the core 50, which core is then protected by the side plates 51 and 52, and the end cover plates 53 and 54, which also serve to establish the pedestal portions or feet 55, and also includes the top plate 56, preferably of bakelite or fiber or the like. The binding posts 45, 46, 47 and 48 are placed in the four corners of the block 56, as indicated in Fig. 5. The two binding posts 45 and 47 are preferably connected to clips 57, and 58 between which may be snapped the block 59 constituting the grid leak. The condenser 36 being relatively thin and of small size may be suspended at one side of the coil 49 by means of a lug 60 which reaches downwards from the binding post 45. The other side of said condenser is preferably connected by a wire 61 leading across through the core 50 to the other side of the unit where it is conveniently connected to the binding post 46. One side of the coil 49 also connects to the lead 61. The other side of the coil connects directly to the binding post 48, in accordance with the diagram illustrated.

It will be noted that the two cover plates 51 and 52 are preferably bulged outwards, as best illustrated in Fig. 7, so as to give the unit a more finished appearance and also to establish additional space for the accommodation of the condenser 36.

It will also be noted that the upper portion of the cover plates 51 and 52 are preferably drawn inwardly somewhat so as to register flush with the edges of the top plate 56. Said plate may also be recessed in its top face, as illustrated at 62 in Fig. 5, so as to receive a name plate or other symbol.

Referring now to Figs. 3 and 4, I have therein illustrated diagrammatically an arrangement very similar to that of Figs. 1 and 2, with the exception that the positions of the reactance coil 38 and grid leak 32 have been reversed, the coil being placed at the plate side of the detector tube 8 and the grid leak at the grid side of the amplifier tube 9. With the exception of the foregoing changes, the two circuits are very similar in arrangement and operation.

In order to adapt the unit itself convenient-

ly to the connections of the circuit of Fig. 3, the four binding posts 45, 46, 47 and 48 are preferably marked to indicate the elements to which they are intended to be connected. 5 Thus, the binding post 45 will be marked G instead of P, the binding post 46 will be marked P instead of G, and the binding post 47 will be marked N. F. instead of Plus, and the binding post 48 will be marked Plus instead of N. F. 10

It will be understood that in case there is more than one stage of amplification, another unit may be set between the tube 9 and the next tube of the series, etc., these units being 15 placed at the succeeding stages of amplification.

Owing to the fact that there is but a single coil in each of the translation units, any distortion and other deleterious effect will be 20 greatly reduced, so that the tones will be translated from stage to stage in a much more perfect and true condition than is possible in the case of the use of ordinary transformers having primary and secondary windings. 25

Furthermore, the elimination from the unit of one or more windings such as are found in ordinary transformers will materially reduce the cost and complication thereof with resultant benefits which can only be appreciated 30 by actual use of the present units in service.

Referring to Fig. 1 it will be noted that the coil 38 serves the additional function of at all times by-passing negative charges accumulating at the grid 14 of the amplifier tube, and 35 passing them to the filament of said tube. A similar function with respect to the grid 11 of the detector tube 8 is performed by the coil 28.

Referring also to Fig. 1, the coil 38 is of 40 such relatively low resistance as to allow direct current accumulated on the grid to flow to the filament but the impedance of said coil is sufficient to avoid interference with proper functioning of the tube.

45 In many cases it may be desirable to tap the condenser into the body of the winding 38 of Fig. 1 as shown by the dotted line 38^a of the modification shown in Fig. 8 instead of connecting directly to the end of said winding, 50 leaving the grid connected to the end of said winding or to tap the plate 12 of Fig. 3 into the body of the winding 38 of said figure as shown by the dotted line 38^b of the modification shown in Fig. 10, leaving the condenser 55 connected to the end of said winding. This will be the case, for example, where it is desired to increase the ratio of amplification.

While I have herein shown and described only certain embodiments of the features of 60 my present invention, still I do not intend to limit myself thereto, except as I may do so in the claims.

I claim:

1. The combination with a detector tube 65 and amplifier tube of a radio carrier wave

receiving set, each tube having a filament, a grid and a plate, and an A battery for illuminating the filaments and a B battery, of a self-contained transfer unit interposed between the plate of the detector tube and the 70 grid of the amplifier tube, said unit including a fixed condenser of substantially .06 mf. capacity connected directly between said plate and grid, a resistance of substantially one-half meg-ohm connected directly between the plate side of the condenser and the positive side of the B battery, and a reactance coil of substantially 100 to 200 henries connected directly between the grid side of the condenser and the negative side of the battery, substantially as described. 75

2. The combination with a detector tube and amplifier tube of a radio carrier wave receiving set, each tube having a filament, a grid and a plate, and an A battery for illuminating the filaments and a B battery, of a self-contained transfer unit interposed between the plate of the detector tube and the 80 grid of the amplifier tube, said unit including a fixed condenser connected directly between said plate and grid, a resistance connected directly between the plate side of the condenser and the positive side of the B battery, and a reactance coil connected directly between the grid side of the condenser and the negative side of the battery, substantially as described. 85

3. The combination with a detector tube and amplifier tube of a radio carrier wave receiving set, each tube having a filament, a grid and a plate, and an A battery for illuminating the filaments and a B battery, of a self-contained transfer unit interposed between the plate of the detector tube and the 90 grid of the amplifier tube, said unit including a fixed condenser connected directly between said plate and grid, a resistance connected directly between the plate side of the condenser and the positive side of the B battery, and a reactance coil connected directly between the grid side of the condenser and the 95 negative side of the battery, substantially as described. 100

4. As a new article of manufacture, a self-contained transfer unit for the purpose specified including in combination a fixed condenser of substantially .06 mf. capacity, a resistance of substantially one-half meg-ohm having one end connected directly to one side of said condenser, a reactance coil of substantially 100 to 200 henries having one end connected directly to the other side of the condenser, and binding posts connected to both ends of the reactance coil and to both ends of the resistance, substantially as described. 110

5. As a new article of manufacture, a self-contained transfer unit for the purpose specified including in combination a fixed condenser, a current resisting conducting element having one point connected directly to one side of said condenser, a tapped reactance coil having one point connected directly to

the other side of said condenser, means for connecting to at least two points of the current resisting conducting element, and means for connecting to at least two points of the reactance, substantially as described.

HENRY E. BURKET.
